UNITED STATES PATENT OFFICE.

JAMES E. GLEASON, ARTHUR L. STEWART, AND WILBUR H. SNOW, OF ROCHESTER, NEW YORK, ASSIGNORS TO GLEASON WORKS, OF ROCHESTER, NEW YORK, A CORPORATION OF NEW YORK.

GEAR-GENERATOR.

1,236,836.

Specification of Letters Patent. Patented Aug. 14, 1917.

Application filed March 12, 1917. Serial No. 154,178.

To all whom it may concern:

Be it known that we, JAMES E. GLEASON, ARTHUR L. STEWART, and WILBUR H. SNOW, all of Rochester, in the county of Monroe 5 and State of New York, have invented certain new and useful Improvements in Gear-Generators; and we do hereby declare the following to be a full, clear, and exact description of the same, reference being had to 10 the accompanying drawings, forming a part of this specification, and to the reference-numerals marked thereon.

The invention relates to gear generators with particular reference to machines for 15 cutting bevel gears, and is in the nature of an improvement on the structure disclosed in an application filed by James E. Gleason, May 26, 1913, Serial No. 769,808, which is now pending, and the purpose of the present 20 mechanism is to adapt the machine of the aforesaid application to the generation of gears by a different principle, consisting in rolling the gear blank on a bevel gear segment or cone instead of on a crown gear or 25 plane surface, or otherwise producing a relative movement between the gear blank and cutter that will correspond to or afford the same generated effect as rolling the gear blank on a conical or bevel surface. To 30 these and other ends the invention consists in certain improvements and combinations of parts all as will be hereinafter more fully described, the novel features being pointed out in the claims at the end of the specification. 35

In the drawings:

Figure 1 is a horizontal sectional view with parts in elevation, showing the application of the present improvement;

Fig. 2 is a side elevation;

Fig. 3 is a vertical central sectional view, with the cutter and supporting parts in elevation, and

Fig. 4 is a detail view.

Similar reference numerals in the several figures indicate the same parts.

The general arrangement and driving mechanism of the present case is substantially similar to that of the former application referred to, and inasmuch as such features as are disclosed in the pending application form no part of the present invention, it is not deemed necessary to describe all the parts in detail and it will be sufficient to designate them in a general way

only, sufficiently for understanding the present construction. 1 designates a portion of the machine base on which is mounted a cradle 2 provided with flanges or ribs 3 that are guided in the tracks 4. The cradle 2 has 60 adjustably mounted thereon a supporting plate 5 provided with a standard 6 which supports a work spindle 7. The base of the machine also includes a frame 8 upon which a bed plate 9 is arranged, swinging or pivoting about the central arbor 10, and adjustably arranged on the bed plate 9 is an upright support 10 having arranged therein the cutter spindle 11 upon which is secured a cutter head 12 provided with planing tools 70 or cutters 13 which travel across the face of the gear blank 14 in a circular path when the cutter spindle is rotated, and acting as a rotary face milling cutter, as will appear clearly from Fig. 2.

The longitudinal curvature of the tooth of a gear is determined by the circular travel of the tools, the cutting edges of which are preferably straight sided, and in order to generate the sides or profile of the tooth 80 properly, that is to say, to impart the proper shape to the tooth from top to bottom, as distinguished from end to end, it is intended to impart a relative profile generating movement to the cutter head and gear 85 blank, corresponding to the relative movement of mating bevel gears when one is rolling upon the other, and this is preferably carried out by giving a generating movement to the blank carrier, whereby the blank 90 moves with reference to the cutter head as if it were rolling around a cone or segment of a bevel gear. In the present embodiment, the cradle 2 is moved back and forth on the tracks 4 to impart this generating movement to the gear blank during rotation of the cutter head, and the supporting plate 5 and standard 6 are so positioned on the cradle 95 that the longitudinal direction of movement of the cradle during its generating motion is 100 longitudinally of the axis of the blank carrier or spindle 7. Expressing it in another way, the longitudinal direction of the tracks 4 is at an acute angle to the rotary axis of the cutter head. Since the gear blank axis 105 7 extends in the same longitudinal direction as the generating travel of the cradle, or of the tracks 4, when the cradle is moved, it rolls the gear blank as around a conical surface, a section of which is represented by 110

the cutter in action at any particular moment. In the application previously referred to, the direction of movement of the cradle was at right angles to the rotary axis 5 of the cutter spindle, the effect of which was to roll the gear blank on a plane or flat surface corresponding to a rack, or crown gear, whereas with the present arrangement the gear blank is rolled as on a bevel surface or 10 segment of a cone, and this may be accomplished in other ways than that particularly described, so that the invention is not to be confined to a machine in which the blank itself is moved to obtain the generating action 15.

The blank spindle is indexed through any suitable index gearing designated generally by 15, motion for which may be obtained from the electric motor 15^a, this being a conventional and well known form of index mechanism. 16 is the main driving pulley and operates through suitable gearing to move the connecting rod 17 back and forth for imparting the necessary oscillating movement to the cradle. Motion is also obtained from the driving pulley 16, through suitable gears, for rotating the cutter spindle 11 constantly, and through the cam wheel 18, the bed plate 9 is intermittently rocked about 20 the axis 10 to withdraw the cutter head from operative engagement with the gear blank, which is then indexed to bring another portion of the blank into cutting position. 25

35 In order to roll the blank past the cutter, when the cradle is operated, the spindle 7 is arranged in a sleeve 19 which carries a splined collar 20, supported in the standard or bracket 6. The collar 20 has fixed on it 40 an extension 21, provided with a segment of a bevel gear 22, and this latter engages a co-operating bevel gear segment 23 that is fixed on the frame of the machine. Thus, as the cradle is moved, the gear blank is 45 turned and rolled in accord with the movement of bevel segment 22 on the stationary bevel segment 23, giving the blank a movement as if rolling about a cone or bevel segment, instead of on a crown gear or plane 50 surface.

It will be understood that with this type of machine the cutter head is held in engagement with the blank until one side face of a tooth is completed, and the blank is then indexed during the time that the cutter is withdrawn and by the time the cutter is returned to operating position by swinging the bed plate 9 about the axis 10^a, the next tooth on the blank will have been brought into position to be engaged by the cutting tools. 60

We claim as our invention:

1. In a machine for producing curved tooth bevel gears, the combination with a blank carrier and a cutter and means for effecting relative movement thereof to cut a 65

curved slot, of means acting to produce a relative profile generating movement between the blank and cutter corresponding to the relative movement of the blank and a mating bevel gear when one is rolling upon the other. 70

2. In a machine for producing curved tooth bevel gears, the combination with a blank carrier and a cutter and means for effecting relative movement thereof to cut a 75 curved slot, of means acting to produce a relative profile generating movement between the blank and the cutter corresponding to the movement of the blank on a conical section. 80

3. In a machine for producing curved tooth bevel gears, the combination with a blank carrier and a cutter and means for effecting relative movement thereof to cut a 85 curved slot, of means acting to produce a profile generating movement of the blank past the cutter corresponding to rolling the blank on a bevel segment, a section of which is represented by the cutter. 90

4. In a machine for producing curved tooth bevel gears, the combination with a blank carrier and a rotary face milling cutter movable across the face of the blank, of means acting to produce a relative profile generating movement between the blank and the cutter corresponding to the relative movement of the blank and a mating bevel gear when one is rolling upon the other. 95

5. In a machine for producing curved tooth bevel gears, the combination with a 100 blank carrier and a rotary face milling cutter movable across the face of the blank, of means acting to produce a relative profile generating movement between the blank and the cutter corresponding to the movement of 105 the blank on a conical section. 110

6. In a machine for producing curved tooth bevel gears, the combination with a blank carrier and a rotary face milling cutter movable across the face of the blank, of 110 means acting to produce a profile generating movement of the blank past the cutter corresponding to rolling the blank on a bevel segment, a section of which is represented by the cutter. 115

7. In a machine for producing curved tooth bevel gears, the combination with a blank carrier and a rotary face milling cutter each tool of which is movable across the face of the blank in a circular path, of means 120 acting to produce a relative profile generating movement between the blank and the cutter corresponding to the relative movement of the blank and a mating bevel gear, when one is rolling upon the other. 125

8. In a machine for producing curved tooth bevel gears, the combination with a blank carrier and a rotary face milling cutter each tool of which is movable across the face of the blank in a circular path, of 130

means acting to produce a relative profile generating movement between the blank and the cutter corresponding to the movement of the blank on a conical section.

- 5 9. In a machine for producing curved tooth bevel gears, the combination with a blank carrier and a rotary face milling cutter each tool of which is movable across the face of the blank in a circular path, of
10 means acting to produce a profile generating movement of the blank past the cutter corresponding to rolling the blank on a bevel segment, a section of which is represented by the cutter.
- 15 10. In a machine for producing curved tooth bevel gears, the combination with a blank carrier and a rotary face milling cutter each tool of which is movable across the

face of the blank in a circular path, of means acting to produce a profile generating movement of the blank past the cutter in a direction extending at an acute angle to the rotary axis of the cutter.

11. In a machine for producing curved tooth bevel gears, the combination with a blank carrier and a rotary face milling cutter each tool of which is movable across the face of the blank in a circular path, of means acting to produce a profile generating movement of the blank bodily past the cutter in a direction parallel to the gear blank axis.
